UNITED STATES PATENT OFFICE.

FRED ADOLPH BRUNEL, OF HEMPSTEAD, NEW YORK.

TOY.

1,248,068.

Specification of Letters Patent. Patented Nov. 27, 1917.

Application filed May 19, 1917. Serial No. 169,712.

To all whom it may concern:

Be it known that I, FRED A. BRUNEL, a citizen of the United States, residing at Hempstead, Long Island, in the county of 5 Nassau and State of New York, have invented certain new and useful Improvements in Toys, of which the following is a specification.

This invention relates to toys and has as its object to provide a toy which will be both amusing and instructive to children and which comprises a number of pieces which may be assembled in various manners to form the letters of the alphabet, numerals, and figures resembling articles or structures such as chairs, wind-mills, etc.

The invention contemplates the provision of a number of rigid pieces and a number of jointed pieces designed to serve as connections between the rigid pieces or as terminal members, the joints being of such a nature as to permit of the jointed pieces being employed in various combinations so that with a relatively small number of such jointed pieces a relatively large number of combinations may be produced.

In the drawings:

Figure 1 represents a number of the pieces assembled to form the letter A;

Fig. 2 represents a number of the pieces assembled to form the letter K;

Fig. 3 is a perspective view of one of the jointed pieces;

Fig. 4 is a view partly in elevation and partly in section illustrating one manner of using the joints shown in Fig. 3;

Fig. 5 is a perspective view of another form of joint, the parts being disassembled;

Fig. 6 is a view illustrating the joints arranged to form the letter L;

Fig. 7 is a similar view illustrating the joints arranged to form the letter Q;

Fig. 8 is a similar view illustrating the joints arranged to form the letter X;

Fig. 9 is a perspective view of another form of joint;

Fig. 10 is a vertical sectional view illustrating another arrangement of the joints shown in Fig. 5.

As before stated, the toy embodying the present invention consists of a number of straight rigid pieces and a number of jointed pieces. Each of the straight rigid pieces is indicated by the numeral 1 and any number of these pieces may be provided and each is in the nature of a tube the ends of which

serve as sockets or the pieces may be solid and provided at each end with a socket. One of the jointed pieces is shown in Fig. 3 of the drawings and the same comprises two arms, one indicated by the numeral 2 and the other by the numeral 3. The arm 2 at one end is reduced and flattened to form an ear 4 and relatively inclined shoulders 5 located at the opposite sides of the said ear. 65 The arm 3 at one end is bifurcated to form spaced ears 6 and at the inner end of the bifurcation the said end of the arm has oppositely inclined shoulders 7 located between the inner ends of the said ear 6. The arms 2 and 3 are connected by fitting the end of the ear 4 between the outer ends of the ears 6 and inserting a pivot pin 8 through the said ears. By reference to Fig. 4 of the drawings it will be observed that in forming certain combinations the edges of the ear 4 may engage against one or the other of the shoulders 7 at which time the edges of the ears 6 will engage against one or the other of the sets of shoulders 5. It will be understood by reference to this figure and to several of the other figures of the drawings that the jointed members are to be assembled with the tubular members 1 by fitting the free ends of the arms of the jointed members into the sockets provided at the ends of the said tubular rigid members. While Fig. 4 is of a fragmentary nature it will be understood that if the tubular members were shown in their entirety the letter V would be formed and the distance to which the said members 1 may be brought toward each other is limited by the engagement of the shoulders of the arms comprising the jointed pieces. The arms 2 and 3, however, 95 may be swung upon their pivot 8 so as to assume various angular positions with relation to each other. In Fig. 1, for example, in forming the letter A two of the pieces shown in Fig. 3 are employed at the upper 100 corners of the letter to connect the top bar of the letter and the side bars thereof above the lower or cross bar and in this combination the arms 2 and 3 of each piece extend at right angles with relation to each other. 105 As shown in Figs. 6 and 7 of the drawings one of the pieces shown in Fig. 3 may be employed as a terminal part of a letter such, for example, as the letter L in Fig. 6 or the stem of the Q in Fig. 7.

The jointed piece shown in Fig. 5 of the drawings comprises a straight arm 9 which

is formed mid-way between its ends with a slot 10 which extends longitudinally and the end walls of which are beveled to form oppositely inclined shoulders 11. This piece 5 also includes two arms indicated by the numeral 12 each of which has a flat ear 13 having a perforation 14 and provided with oppositely inclined shoulders 15 at the opposite sides of its said ear 13. The ears 13 of 10 the two arms may be fitted in overlapped relation into the slot 10, and a pivot pin 16 is fitted through the registering openings 14 and through aligned openings 17 formed in the opposite side walls of the slot 10. This 15 piece may be employed in the formation of the letter K, as shown in Fig. 2 of the drawings, or by removing the pin 16, which may be accomplished readily due to the provision of a head 18 at one end of the said pin, one 20 of the arms 12 may be removed and disposed at the other side of the arm 9 so as to provide for the formation of the letter X as shown in Figs. 8 and 10 of the drawings. It will also be understood that the arms 12 may 25 be arranged to extend in opposite directions from the opposite sides of the arm 9 in alignment with each other and that, in fact, the three arms may be assembled and adjusted to assume various angular positions with 30 relation to each other.

The jointed piece shown in Fig. 9 of the drawings comprises an arm 20 having spaced ears 21, and two arms 22, each of which has an ear 23. The several arms are assembled 35 by overlapping the ears 23 and disposing the same between the ears 21 of the arm 20 and then passing a pivot pin 24 through all of the said ears. The arms comprising this piece may be adjusted to assume the relative 40 positions shown in Fig. 9 of the drawings in which the arms 22 are in alignment and the arm 20 extends at right angles with relation thereto and so adjusted the piece may be employed as, for example, in forming the letter 45 A, as shown in Fig. 1. When it is desired to form the letter Y, for example, the arm 20 may be vertically disposed and the arms 22 may be adjusted to incline upwardly in 50 diverging lines to form the branches of the letter, one of the rigid members being ap-

plied to the free end of each arm 22 and one to the lower end of the arm 20.

Having thus described the invention, what is claimed as new is:

1. A device of the class described comprising elements to be assembled, to form various structures or figures, including rigid members having sockets, and jointed members having ends for selective insertion in said sockets and to be detachably held 60 therein. 55

2. A device of the class described comprising elements to be assembled, to form various structures or figures, including rigid members having terminal sockets, and jointed members having ends for selective insertion in said sockets and to be detachably held 65 therein. 55

3. A device of the class described comprising elements to be assembled, to form various 70 structures or figures, including rigid tubular members, and jointed members having ends for selective insertion in the ends of the said tubular members and to be detachably held therein. 75

4. A device of the class described comprising elements to be assembled, to form various structures or figures, including rigid members having sockets, and a joining piece comprising pivotally connected arms provided 80 with coacting abutments to limit their adjustment, the ends of the arms being arranged for selective insertion in said sockets and to be detachably held therein. 80

5. In a device of the class described, a 85 joining piece comprising a slotted arm, and arms having overlapped pivot ears removably fitted into the said slot, and a pivot pin removably fitted through the walls of the slot and through the said ears. 90

6. A device of the class described comprising elements to be assembled, to form various structures or figures, including rigid tubular members having sockets, and a joining member comprising pivotally connected arms angularly adjustable and adapted to be fitted at their outer ends selectively into the said sockets. 95

In testimony whereof I affix my signature.
FRED ADOLPH BRUNEL. [L. S.]
